UNITED STATES PATENT OFFICE.

MICHAEL TANENBAUM, OF BROOKLYN, NEW YORK.

DRILL.

1,398,814.

Specification of Letters Patent. Patented Nov. 29, 1921.

Application filed July 15, 1921. Serial No. 485,083.

To all whom it may concern:

Be it known that I, MICHAEL TANENBAUM, a citizen of the United States, residing at Brooklyn, in the county of Kings and State of New York, have invented new and useful Improvements in Drills, of which the following is a specification.

This invention relates to drills and is an improvement on the invention shown in the 10 patents to Benjamin Kunitz #1,140,988 and 1,237,064.

The principal object of the present invention is to provide a new and simplified bowl structure for a drill of this nature.

Another object is to simplify and improve the various elements of the drill structure *per se*.

Another object is to produce a device of this nature which shall be simple and cheap 20 of construction, and highly efficient for the purpose for which it is designed.

With these and other objects in view the invention resides in certain novel construction and combination and arrangement of 25 parts, the essential features of which are hereinafter fully described, are particularly pointed out in the appended claims, and are illustrated in the accompanying drawing, in which:

Figure 1 is a side elevation of my improved drill.

Fig. 2 is a longitudinal sectional view of the same.

Fig. 3 is an end view of the same.

Fig. 4 is a perspective view of the bowl *per se*.

Fig. 5 is a perspective view of the bushing or sleeve *per se*.

Fig. 6 is a side elevation of the center 40 point member.

Fig. 7 is a perspective view of the knurled collar.

Fig. 8 is a perspective view of one of the scribing tools, and

Fig. 9 is a view of one of the large knives.

Fig. 10 is a perspective view of one of the tool holders for the scribing tools.

Like characters of reference refer to like parts in all views.

Referring to the drawing in detail, 10 represents a length of tubing which is swaged down at 11 into a suitable form for being held in an ordinary brace. Upon the end of this member is threadedly secured 55 a head 12 having radiating arms 13 each of which is provided with a radial slot 14 in its

outer face. Apertures are drilled in each of the members 13 transversely of the slots 14 and set screws 15 pass through these apertures which are threaded at one end so as 60 to hold the screws when seated therein. Two knives 16 for removing the major portion of the plaster or other material are provided for each device and each of these knives comprises a shank 17 which slides 65 in one of the ways 14. The shank 17 is formed with a slot 18 through which the screw 15 passes. It is obvious that these knives are therefore adjustable radially of the device. Only one knife is adjusted, the 70 other being left in inner position to remove the inner material from the hole, although both are adjustable and either may be adjusted when desired.

Slides 19 are seated in the remaining two 75 ways 14 and are provided with slots 18^a similar to those in the above described knives. In this way slides 19 are also adjustable radially of the device. Each of the slides 19 is provided with a dove-tailed 80 way 20 and with a clamp 21 co-acting with said way to hold a scribing tool or knife 22 in position. The knife 22 is provided at one end as at 23 with a flat cutting portion for use in slicing or scribing the paper and 85 plaster or other material before the knives 16 remove the same so that an even and smooth cut is made with no rough or jagged edges. The other end of the tool is provided with a cutting portion 24 which may 90 be used when sheet metal or plain plaster is to be removed. The knives 22 should be set out far enough to cut or scribe in advance of the larger knives. A sleeve or bushing 25 is seated in the end of the tubing 10 and 95 head 12, the outer end of said sleeve being enlarged as at 26 so as to form a shoulder which rests against the top of the head 12 and prevents the sleeve from falling down therein. A set screw 27 secures the bushing 100 in place and a thumb screw 28 passing through a slot 29 in the sleeve prevents rotation of the sleeve. A conical spring 30 prevents loosening of the screw 28 by vibration. The slot 29 is made of some length 105 so that the sleeve may be adjusted longitudinally of the head 12.

A center point member 31 is provided with a shoulder 32 adapted to seat itself in the end of the sleeve 25 and against the inner shoulder formed at 26. The shank of this center point member is provided with a

groove 33 adapted to receive the end of the thumb screw 28 so as to lock it in place. The outer portion of this member is formed into a center blade as shown at 34.

5 A tool of this nature is intended for use where electric installation is to be made in houses not so equipped during the building and in boring suitable holes in the ceiling or walls of any room in which to place the required outlet box, considerable annoyance and damage has been caused by the falling plaster where these drills are not used. In the former patents on a device of this nature which patents have been hereinbefore referred to the bowl structure for catching the debris has not been of the most advantageous type and the present bowl structure is designed so that it may be quickly adjusted along the tubing 10 to any desired position, 10 and this is of great advantage inasmuch as the bowl may be kept very close to the ceiling during the entire operation and shifted down a little bit at a time without requiring any loss of time in adjusting set screws and 15 so forth.

20

25

The present bowl structure comprises a cupped member 35 which is apertured and drawn out at 36, the portion 36 being soldered or otherwise secured to a length of 30 tubing 37 of a size to fit snugly and yet slip freely along the tubing 10. Secured to the lower end of the tube 37 is a knurled member 38 carrying a spring 39 which projects a slight distance into the central aperture so 35 as to frictionally engage the tubing 10. With this structure it will be readily seen that the bowl may be quickly and easily positioned along the tube 10 and at the same time will be held securely in any adjusted 40 position by the spring 39.

In using the device it is often found that a gas pipe is in the center of the hole to be bored, and in this case the center point member 31 is removed and the pipe allowed to 45 protrude into the sleeve 25, the sleeve and gas pipe forming a center anchor for holding the device in central position during the drilling operation. Inasmuch as the size of the gas pipe may vary, the sleeve is made 50 of an internal diameter substantially the same as the external diameter of the smaller size gas pipes and of an external diameter substantially the same as the external diameter of the larger size gas pipes. In case the 55 larger size of gas pipe is encountered the

sleeve is removed and the pipe allowed to project down in the tube 10.

What is claimed as new is:—

1. A drill comprising a shank, a head removably mounted on said shank and including a plurality of radial ways formed in its upper face, knives adjustable in certain of said ways, and knife carriers adjustable in other of said ways. 60

2. In a device of the class described, the combination of a tubular shank having one end formed into an engaging element, a knife head seated on the other end of said shank and comprising a plurality of radial ways, knives adjustably seated in certain of said ways, a sleeve seated in said head and formed with a shoulder for engagement with said head, and a center point member seated in said sleeve and formed with a shoulder coöperative with the shouldered end of said 70 sleeve. 75

3. In a device of the class described, the combination of a tubular shank having one end formed into an engaging element, a knife head seated on the other end of said shank and comprising a plurality of radial ways, knives adjustably seated in certain of said ways, a sleeve seated in said head and formed with a shoulder for engagement with said head, a center point member seated in 80 said sleeve and formed with a shoulder coöperative with the shouldered end of said sleeve, and a screw for securing sleeve and center point member in adjusted position 85 with relation to said head. 90

4. A device of the class described comprising a shank, a cutting head removably secured to said shank, a bowl slidably mounted on said shank, a spring for securing said bowl in adjusted position on said shank, and a housing for said spring and secured to said bowl so as to form a finger piece for moving said bowl. 95

5. A device of the class described comprising a shank, a cutting head removably secured to said shank, a sleeve slidable on said shank, a bowl secured to said sleeve, a spring for securing said bowl in adjusted position on said shank, and a housing for said spring and threadedly engaging said sleeve as and 100 for the purpose set forth. 105

In testimony whereof I have affixed my signature.

MICHAEL TANENBAUM.
